UNITED STATES PATENT OFFICE.

ABNER JOHNSTON, OF JERSEY CITY, NEW JERSEY, ASSIGNOR OF TWO-
THIRDS TO GEORGE B. FIELDER, OF SAME PLACE, AND GEORGE R.
JOHNSTON, OF ETNA, NEW JERSEY.

CUT-OUT PLUG.

SPECIFICATION forming part of Letters Patent No. 628,180, dated July 4, 1899.

Application filed March 25, 1898. Serial No. 675,162. (No model.)

To all whom it may concern:

Be it known that I, ABNER JOHNSTON, a citizen of the United States, residing at Jersey City, in the county of Hudson and State of New Jersey, have invented certain new and useful Improvements in Cut-Out Plugs; and I do hereby declare the following to be a full, clear, and exact description of the invention, such as will enable others skilled in the art to which it appertains to make and use the same.

This invention relates to electric cut-outs, and particularly to that class of these devices commonly known as "cut-out plugs."

The object of the invention is to construct such a plug that the fuse may be readily put in place and perfect electric contact made with the terminals of the plug without the use of solder.

With this end in view the invention consists in the construction hereinafter fully described and claimed.

In the accompanying drawings, which form a part of this specification, Figure 1 represents a vertical central section through a cut-out plug embodying my invention. Fig. 2 is a similar view representing a modification in the adaptation of the invention, while Fig. 3 is a like view of the cut-out plug as ordinarily constructed.

The cut-out plug, in the main, is of the usual construction, my invention having to do simply with the terminals and the mode of connecting the fuse thereto. Therefore A indicates the vitreous or glass cup; B, the cap therefor; C, the lower terminal, and D the other or lateral terminal, the tongue, as E, extending from the terminal D through the wall of the cup in the usual manner and the lower terminal being secured in place by plaster-of-paris or other friable material by which the interior of the cup may be coated, as indicated at F.

In the form of plug as ordinarily constructed and as shown in Fig. 3 the fuse-wire G is soldered at its ends to the tongue E and the upper end of the terminal C. It is a difficult matter to accomplish this soldering because of the readily-fusible nature of the wire G and because of the small space within which

to manipulate the soldering-iron in connecting the wire to the terminal C, and much time is consumed in inserting the fuses by this old mode of procedure. These difficulties are readily obviated by forming upon or otherwise securing to the inner end of the terminal C an open clamp or hook, such as shown at H, and by connecting to or forming upon the tongue E a like clamp or hook, as shown at I. With the two terminals thus equipped with clamps it is an easy matter to insert the fuse. It is done by simply making a loop in the lower end of the piece of fuse-wire and pulling the loop firmly up into the hook H and then pressing or drawing the fuse-wire into the hook I, where it is readily pinched or broken off by the fingers above said hook. The fuse-wire, being exceedingly malleable, is easily squeezed or wedged into these hooks, so as to make a firm and close electrical contact therefor and to produce as good results as can be produced by soldering.

It is obvious that fuses may be inserted in the improved cut-out with far greater rapidity than they can be where they are soldered in place.

If desired, more than one hook may be used on the terminals of the plug, as indicated in Fig. 2, wherein two hooks are shown upon each plug and the fuse-wire caught under each hook. This may be done by forming a double loop at the lower end of the wire and pulling it up so as to wedge its parts snugly into the hooks H' and then drawing the upper end of the fuse-wire tightly into hooks I'.

Any other suitable forms of open hooks or clamps may be used other than those shown without departing from the spirit of my invention, the essential requisite being that the hook shall be convergent or gradually constricted toward the inner end, whereby the fuse-wire will be clamped the more tightly the farther it is pulled into the hook and whereby the same clamps or hooks are adapted to receive fuse-wires of different gages.

The invention claimed is—

In a cut-out plug, the combination of the plug-cup, the lower terminal located in the bottom of said plug-cup and terminated by

an open convergent hook, the lateral terminal also terminated by an open convergent hook, located at the side of said plug-cup, near its top, and a fuse-wire, with its lower looped end adapted to be caught into the hook of said lower terminal and its upper end tightly drawn into the hook of the said lateral terminal, substantially as set forth.

Signed at New York, in the county of New York and State of New York, this 23d day of 10 March, A. D. 1898.

ABNER JOHNSTON.
